UNITED STATES PATENT OFFICE.

ALFRED WILKINSON, OF WALLASEY, ENGLAND, ASSIGNOR TO MULTIPLE ADVERTISING CLOCK CO., LIMITED, OF LONDON, ENGLAND.

INDICATING AND ADVERTISING DEVICE.

Application filed April 14, 1925, Serial No. 23,064, and in England May 27, 1924.

This invention relates to an improved indicating device suitable for displaying advertisements or useful information.

The invention is applicable to an indicating device in which advertisements or other useful information are displayed on a plurality of movable leaves mounted on a rotatably member or members so that different pairs of leaves can be brought into view.

The invention consists in providing an automatic advertisement or the like device in which advertisements are displayed on a plurality of leaves which are adapted to be turned so as to bring different advertisements in view at predetermined intervals of time.

A further feature of the invention consists in the combination of an automatic advertising or the like device in which different advertisements are automatically brought into view at predetermined intervals, with a time indicating or time recording device. In this case the advertising device is preferably controlled by the movement of the time indicating device.

In any of the forms of the device automatic control mechanism for displaying the advertisements or the like at predetermined times may be supplemented by another control mechanism which can be operated at will or on the performance of the specific action such as the pressing of a button.

An important feature of the invention is the provision of a spring device adapted to be released by the control mechanism referred to and to operate automatically the change of advertisement or indicator. A further important feature is the use of such a spring operated indicator controlled by a clock movement to display information accurately at predetermined intervals.

A preferred form of the invention will be described with reference to the accompanying drawings, in which:

Figure 1 is a front elevation of a combined clock and advertisement displaying device.

Figure 2 is a section on the line A—B showing a few of the leaves carrying the advertisements.

Figure 3 is a plan view showing a few of the leaves and one form of the stop and release mechanism.

Figure 4 shows a broken elevation of two of the leaves.

An ordinary clock movement not shown is mounted in a wooden base 1 with the main spindle 2 directed vertically. The usual friction engagement between the main spindle and the driving mechanism is provided. On this main spindle is mounted a main shaft 3 carrying a lower plate 4 and an upper plate 5 and having on its upper end a bevel gear wheel 6. The bevel gear wheel 65 engages a corresponding bevel gear wheel 7 on the finger spindle of a clock 8. In a device having the same number of teeth in both bevel wheels the main axle will thus rotate once every hour. The clock spindle 70 is provided with the usual friction engagement to enable the hands to be moved, if desired, independently of the main shaft.

The plates mounted on the main shaft each have, for example, twenty small orifices 9 equally spaced round the periphery. The advertisement or display devices consist of twenty rectangular leaves 10 of sheet metal or any other suitable material each of which has a small projection 11 at the top and a projection 12 at the bottom close to the same vertical edge. These projections pass through the orifices 9 in the upper and lower plates respectively and thus act as pivots for the leaves. The positions of the projections and orifices are so arranged that when two adjacent leaves are pressed back in opposite directions they may appear as one continuous sheet. Any desired design or wording may therefore, if desired, be 90 inscribed on the adjacent faces of adjoining leaves.

The lower projection on each leaf passes through the lower plate and rests on a hard steel surface 13 which forms a step bearing. 95 The upper projection 11 passes through the upper plates and on the upwardly projecting portion carries a small spiral spring 14 rigidly attached to the plate and firmly but adjustably attached to the upper end of the projection by the collar 15. The projections 11 are, as shown in Fig. 4 alternately long and short so as to prevent the set screws 20 from fouling each other.

The advertisements are suitably illuminated by one or more concealed lamps 20. The springs are adapted to turn the leaves in the direction of rotation of the main

shaft. Thus if the shaft is rotating and a stop 16 is placed in engagement with the outer edge of a leaf, this leaf and those behind it are pressed back against the 5 springs until finally the rotation presses the front leaf far enough back to be released from the stop, then the action of the spring causes it to fly across the space between itself and the leaf in front and expose a 10 different surface. The action of the springs in conjunction with the rotating shaft is thus continuous and automatic.

The stop may be in the form of a train 17 of freely rotatable wheels or rollers 18, 15 which may be arranged rectilinearly or curvilinearly and may have their axes staggered. Each roller then stops only one leaf at a time so that the leaves are prevented from rubbing against each other.

20 The leaves are printed with advertisements or the like on both faces and it is preferred that the adjacent faces of two adjoining leaves should form one complete design.

25 To facilitate exchange of leaves the two supporting plates may be mounted on a sleeve in frictional engagement with the main shaft. The frictional engagement in the time movement itself may then be dispensed with. In the modification shown in 30 Fig. 1 all the leaves may be removed by lifting the clock from the top, removing the bevel wheel and withdrawing the whole sleeve carrying with it the leaves and their 35 supporting plates.

The leaves may conveniently be removed by unscrewing the collar 15 and bending the leaves so that the projections 9 are disengaged from the plates 4 and 5. To render 40 the leaves accessible a hinged glass cover 19 is provided.

45 The time movement may be continuous or intermittent as desired and may be operated by spring or electromagnetically or in any other manner as desired. The independent ratchet and pawl mechanism for turning the leaves may be operated by hand or electromagnetically as desired.

50 It is clear that the device may be used for many purposes, e. g. for displaying advertisements or for showing theatre programmes or for displaying times of coming events or departure of trains or the like. In conjunction with the time movement the 55 leaves will be turned to display different information at regular intervals of time, e. g. in the above described device having twenty leaves mounted on a shaft rotating once per

hour a leaf will turn every three minutes but clearly any desired number of leaves 60 may be used. Where an independent turning device is also provided it is possible in addition to turn the leaves by hand or to cause one to turn on the ringing of a bell or the operation of any device connected to the 65 independent turning mechanism.

I declare that what I claim is:—

1. A display device comprising a shaft, a pair of plates on said shaft in spaced relation, a plurality of leaves situated between 70 said plates, a pair of stub pivots for each leaf, said pivots being journaled in said plates, one of said pivots projecting through its respective plate and having a collar loose thereon on the opposite side of said plate to 75 said leaf, a torsion spring around each of said extending stub pivots and anchored at its ends upon said collar and said plate respectively, and means for locking said collar to said stub pivot. 80

2. A display device comprising a shaft, a pair of plates on said shaft in spaced relationship, a plurality of leaves situated between said plates, a stub pivot at the inner corner of each leaf projecting directly 85 through one of the plates, and a torsion spring surrounding each stub pivot on the opposite side of the plate to the leaf and anchored at its ends to the stub pivot and to the plate respectively. 90

3. A display device comprising a shaft, a pair of plates on said shaft in spaced relationship, a plurality of leaves situated between said plates, stub pivots supporting said leaves directly in said plates, torsion 95 springs between said pivots and said plates, and a train of rollers engaging individually a plurality of the leaves to distribute the retaining pressure and avoid more than one leaf turning at any time. 100

4. A display device comprising a shaft, a pair of plates on said shaft in spaced relation, a plurality of stiffly flexible leaves situated between said plates, a pair of stub pivots on each leaf, the pivots being coaxial 105 and the line of their axes removed from the adjacent edge of the sheet, whereby two of said sheets may be arranged in a single plane with the surfaces flush and in alignment with each other, said stub pivots having means 110 associated therewith to support said sheet between said plates for rotation about the axis of said pivots. 116

In witness whereof, I have hereunto signed my name this 10th day of March 1925.

ALFRED WILKINSON.
